GRATE STRUCTURE

George Clayton Keown, Albert Lea, Minn., assignor, by direct and mesne assignments, to Master Combustor Company, Albert Lea, Minn., a corporation of Minnesota

Application April 5, 1941, Serial No. 387,089

1 Claim. (Cl. 126—163)

This invention relates to improvements in the class of stoves and furnaces and pertains particularly to an improved grate structure.

The principal object of the present invention is to provide an improved compound or duplex grate structure which provides a novel and improved means of shaking or discharging ashes therefrom and also of providing a novel means of supplying to the burning fuel a greater quantity of air than it is possible to furnish through a grate of ordinary construction, so that the burning of the fuel will be made more nearly complete and the possibility of the development of clinkers and of explosive gases is avoided.

Another object of the invention is to provide an improved grate structure which includes a central reciprocable or sliding section which is movable in the plane of the grate to open a section thereof, together with a pyramidal apertured body supported centrally upon the grate whereby to introduce additional air into the body of the fuel mass lying on the grate for the purpose of improving the combustion, the said reciprocable portion of the grate being movable beneath and independently of the pyramidal body whereby a partial dumping of the grate may be accomplished without interference from the combustion improving portion of the structure.

Another object of the invention is to provide an improved compound or duplex grate structure of the character stated which is designed to be rotated in a horizontal plane and to be partially opened in the manner stated and which is also readily adaptable to any type of stove or furnace whether the same be gravity-fed or hand-fed and whether the same be provided with a forced draft or natural draft means.

The invention will be best understood from a consideration of the following detailed description taken in connection with the accompanying drawing, it being understood, however, that the invention is not to be considered as limited by the specific illustration or description but that such illustration and description constitutes a preferred embodiment of the invention.

In the drawing:

Fig. 1 is a view in vertical section through a portion of a fire box and through the lower part of the grate structure embodying the present invention, the structure being shown supported in the fire box for rotational movement.

Fig. 2 is a view in top plan of the grate structure showing the reciprocable portion partially withdrawn for the dumping of a part of the fire box contents.

Referring now more particularly to the drawing, the numeral 1 generally designates the conventionally illustrated fire box. No fuel or air supply means has been illustrated since this forms no part of the present invention and it will be understood that any suitable type of fuel feed may be employed as well as any suitable form of means for admitting air to the under side of the grate.

10 Within the fire box there is provided a suitable annular support for the grate, which is indicated generally by the numeral 2, and which as shown, is in the form of an angle iron having an inwardly extending flange portion 2^a on which the grate rests. This flange portion provides means not only of supporting the grate but of facilitating the rotation of the grate, within prescribed limits, when it is desired to shake the ashes therethrough. The grate structure is made up of two 15 units which are indicated by the numerals 3 and 4, respectively, and which may be defined as the grate and combustor units. The grate proper comprises an annular frame or rim 5 designed to rest upon the flange 2^a, across which extend 20 in spaced parallel relation and upon the opposite sides of the radial center, the two bars 6 which have their opposed or inner faces provided with guide grooves or slots 7. At one side of the grate frame, the frame is cut out, as indicated at 8, 25 through a circumferential extent equaling the width of the space between the bars 6, so that the ends of the guide slots 7 open through the periphery of the grate or through the frame 5 for alinement with a horizontal slot 9 formed in the 30 wall of the fire box 1. This slot 9 provides a means of withdrawing the hereinafter described shiftable portion of the grate when it is desired to dump a part of the fuel charge, it being understood that the open end of the area between the bars 6, which area is designated A, normally is 35 alined with the slot 9 of the fire box wall.

Upon the outer side of each of the bars 6 are arranged the spaced grate bars 10 while between the guide bars 6 is located the shiftable portion 40 of the grate which is indicated generally by the numeral 3^a and which comprises a centrally cut-out section of the completed annular grate structure, having outer side rails 11, each of which is provided with a flange 12 which has sliding 45 engagement in a groove 7, the transverse front and rear end portions 13 and 14 connecting the side rails and the bars 15, which parallel the rails 11 and the bars 10. This reciprocable portion when fully inserted has the cross-bar 14 50 thereof in position to form a continuation of

the rim 5 of the grate and it will, therefore, be seen that the grate as a whole may be turned or oscillated on the supporting flange 2. To the bar 14 is secured an outwardly extending handle 16 which passes through the slot 9 and facilitates both the reciprocation of the movable portion of the grate and the turning of the grate as a whole.

The combustor unit 4 is in the form of a hollow frusto pyramidal body which is made up of the four substantially triangular side portions 17 which are joined together by tongue and groove connections while the top of the frustum is closed by the slotted or apertured rectangular plate 18. The side walls and top have therein air admission apertures 19 as shown, while the bottom of the frustum is open and receives air through the spaces between the bars 15. The width of the frustum is slightly greater than the opening A, so that the opposite sides of the body 4 rest upon the guide rails or bars 6. Those side walls 17 which rest upon the bars 6 are provided with bolt receiving openings 20 and each opening has engaged therein the hooked end of a J-bolt 21, the threaded shank portion of which extends downwardly between the adjacent bar 6 and a grate bar 10 to receive a securing nut 22 which engages the under sides of the bars and binds the combustion body 4 firmly into position on the grate. The combustion body as shown, is placed in the exact center of the grate and thus it will be readily apparent that when fuel is thrown in on the grate, it will pile up and be evenly distributed around the center and an ample supply of air will be furnished to the interior of the mass of fuel which will bring about the more nearly complete combustion thereof with the elimination of clinkers and the development of dangerous gases which are the result of incomplete combustion.

It will be readily apparent from the foregoing that when the entire duplex grate structure is to be shaken, this may be accomplished when the reciprocable portion 3^a of the grate is fully inserted, by lateral movement of the handle 16, so as to rotate the grate, and that when a portion of the fuel body is to be discharged or dumped, this may be readily accomplished by bringing the grate back to a position where the handle 16 will be centered in the opening or slot 9 and then withdrawing the shiftable portion 3^a of the grate to the desired extent. In all of these operations the fuel combustor will be maintained in its central position and will function to supply the needed air to the burning fuel.

It will be seen that by the employment of the rectangular pyramidal combustor unit 4 within a circular fire box, when the grate and combustor unit are turned or oscillated to shape the grate, the combustor will compress masses of burning fuel between its four sides and the wall of the fire box and act to break up any masses of fuel which may be forming as a result of the com-

bustion and which might possibly result in the formation of clinkers. In other words, the turning action of the combustor unit acts as a pulverizing means for clinkers so that the burning fuel or ashes will be kept in small pieces and choking of the fire box will not occur but on the other hand, the freer passage of air through the fuel will be permitted. It will also be apparent that where the cone or combustor unit is used in a fire box or fire pot in association with the well known conical type of feeder, which feeder would, of course, come down to a position in the fire box where the upper end of the cone would be located inside of its outlet end, the square top 10 of the cone would function to keep the feeding fuel loosened up so as to prevent stoppage or clogging of the fuel around the top of the cone.

While the top of the combustor cone has been illustrated as having air or draft openings 18, it 20 is also contemplated to provide cones with a solid top body. This would function to prevent air from passing directly upwardly through the cone into the overlying bed of unburned fuel, particularly where the cone may be extended into a self-feeder unit and causing the fuel to ignite in the feeder or above the top of the cone. It 25 would also function to keep the fuel lying above the cone at a lower temperature so as to eliminate any possibility of the fuel becoming coked due to excessive heat that might otherwise pass up through the fuel.

No means has been illustrated for introducing a draft into the lower part of the fire pot below the grate. Draft air may be allowed to enter 30 by the usual ash pit door or it may be introduced through a suitable conduit under force. In using a forced draft with the present grate it would be introduced directly into the cone or combustor and consequently, the cone would become a draft 35 distributor and since the vents are of equal number and size on all sides of the cone, the introduced draft would be uniformly distributed for passage through the burning fuel bed.

What is claimed is:

45 A structure of the character stated for disposition within a fire box, comprising a flat grate unit, means for supporting the grate unit for turning on a vertical axis, a body disposed upon the top of the grate unit at the center thereof 50 and comprising four upwardly and inwardly inclined walls secured together at their adjacent edges, a flat top wall disposed between and coupling the top edges of the side walls, the body being secured to the grate to turn therewith and 55 the corners thereof functioning upon the turning of the grate to loosen up the fuel in contact therewith, said side walls having air passing openings therethrough, the grate body having a plurality of bars, and hook bolts engaging in 60 apertures of the side walls of the body and extending between the bars of the grate and having detachable connection with the same.

GEORGE CLAYTON KEOWN.
